UNITED STATES PATENT OFFICE

GEORGE H. WATERHOUSE, OF PROVIDENCE, RHODE ISLAND

CLASP FOR ARTICLES OF JEWELRY

Application filed April 19, 1929. Serial No. 356,440.

13 This invention relates to an improved clasp or fastening-device for connecting the ends of necklaces, neck-chains, bracelets or like articles of jewelry.

16 One object of the invention is to provide a simple and efficient device for the purpose specified constituted by a minimum number of parts and economical to manufacture.

19 Another object of the invention is to provide a clasp which will effect a more secure joinder of the ends of the necklace, chain or the like without chance of their becoming unclasped or detached.

22 Another object of the invention is to provide a device of the type specified which operates without the employment of spring-actuated, pivoted or sliding parts, and which operates as a safety lock to guard against accidental unclasping or releasing of the connected parts.

25 Another object of the invention is to provide a device of the type specified which is neat and ornamental in appearance and free from projections or sharp edges on its surface liable to catch in the garments of the wearer or to scratch and injure the flesh.

28 Further objects of the invention are set forth in the following specification which describes two forms of construction of the device, by way of example, as illustrated by the accompanying drawings. In the drawings:

Fig. 1 is a side view of the improved clasp showing its parts in closed relation connecting the ends of a chain;

Fig. 2 is a similar view showing the parts of the clasp in open relation to permit disconnection of the ends of the chain;

Fig. 3 is a cross-sectional detailed view of the clasp taken on line 3—3 of Fig. 1;

Fig. 4 is a perspective view showing the parts of the clasp in disassembled relation;

Fig. 5 is a view similar to Fig. 1 showing a modified form of the clasp with its parts illustrated in closed relation;

Fig. 6 is a similar view showing the clasp opened to disconnect the ends of the chain;

Fig. 7 is a sectional view of the modified form of clasp shown in Figs. 5 and 6 taken on line 7—7 of Fig. 5; and

Fig. 8 is a perspective view showing the

two parts of the modified form of clasp in disassembled relation.

The present improved clasp comprises only two parts, a member adapted for permanent connection with one end of the chain, necklace or the like and having a hook for attachment with the opposite end of the chain, and a tubular sleeve adapted to slide on said member to close its hook to secure the ends of the chain in coupled relation.

In the embodiment of the invention illustrated in Figs. 1 to 4 the hook-member 2 is constructed from a flat strip of metal such as platinum, gold, silver or plated stock, and the slide 3 is constituted by a suitable length of cylindrical tubing of the same material. The hook-member 2 is of substantially rectangular shape in side view having a rounded portion or ear 4 at one end pierced with a hole 5 for receiving the end link of the chain, 79 necklace or bracelet indicated at 6. The opposite end of the hook-member 2 also has a rounded contour and is provided with a re-entrant slot 7 forming a beak-like hook 8.

The sleeve or slide 3, as before indicated, is formed from cylindrical tubing cut to a length slightly greater than that of the rectangular portion of the hook-member 2. The internal diameter of the tubing is slightly less than the width of the hook-member 2 and, as shown in Figs. 3 and 4, the marginal edges 9 of the latter may be slightly rounded or convexed to conform to the interior of the sleeve 3 so that the latter fits snugly thereagainst.

In assembling the parts of the clasp the tubular slide 3 is slid onto the hook-member 2 whereby the tube will be slightly stretched or distorted with its major diameter extending in the plane of the member 2 and its minor diameter at right-angles to this plane. In other words, the tube is stretched slightly across its axis to cause it to encompass the hook-member 2 whereby the rounded edges 9 of the latter will exert a frictional pressure 95 against the interior of the tube to resist its sliding movement thereon.

The sleeve or slide 3 is slid longitudinally of the member 2 to carry it into the position illustrated in Fig. 2 whereby to uncover the 101

opening 7 of the hook 8. With the parts in this relation the end-link 12 of the chain or other article may be coupled with the hook 8 to attach the parts of the chain in connected relation. The sleeve 3 is then slid to the right, as viewed in Fig. 1, to cause its terminal portion to overhang the end of the hook 8 to close its opening 7. It has been stated that due to the novel method of assembling the sleeve or slide 3 on the hook-member 2 frictional engagement is provided between the parts to resist the sliding movement of the sleeve. Therefore, when the sleeve 3 is slid into the position illustrated in Fig. 1 it cannot be accidentally displaced to open the hook 8. The device thus functions as a safety lock to prevent unwarranted disconnection of the ends of the chain, necklace or other article.

For some purposes, particularly with flat link chains, it is desirable to have the clasp conform somewhat to the shape of the links of the chain and Figs. 5 to 8 illustrate an embodiment of the device having a flat sided slide 15 enclosing the hook-member 16. Referring particularly to Figs. 7 and 8, the sleeve or slide 15 is constructed from flat tubing, being substantially rectangular in cross-section to adapt it to engage snugly around the flat sides of the hook-member 16. In order to effect a frictional binding action between the slide and the hook-member the member 16 is provided with a spring-finger 18 which may be formed by slitting the stock with a fine saw or other instrument. The spring-finger 18 is sprung outwardly from the main portion of the hook-member 16 as illustrated in Fig. 8 so that it must be compressed to allow the slide 15 to be slid thereon. The spring finger 18 is thus caused to exert frictional resistance to the sliding movement of the sleeve 15 whereby to hold it in either opened or closed relation with respect to the hook 19 at the end of the member 16. In use, the device shown in Figs. 5 to 8 operates in the same manner as previously explained in connection with the first described form of construction.

It will be observed from the foregoing that the present invention provides an extremely simple, yet efficient, device for the purpose specified, being composed of but two elements. The hook-member of the clasp may be punched out or struck up from sheet-stock and the sliding sleeve constructed from a length of tubing such as commercially supplied to the trade in various forms and sizes. No special fitting is required in assembling the parts of the device so that the work may be accomplished by unskilled labor. It will also be observed that there are no pivot-pins, rivets, springs or other such mechanical elements employed in the improved device. The simplified form of construction of the clasp not only makes for more economical cost of

manufacture, but also provides against damage or derangement of the parts when the device is put into use.

Heretofore in the art it has been the usual practice to employ swiveled hooks with spring-latches or so-called "jump-rings" having telescoping portions with compression springs for operating the same, the pivoted latches or other spring-actuated parts serving to close the openings to the hook or clasp. With the present improved construction no spring elements are employed and therefore the clasp is rendered much stronger and more durable, while providing a greater degree of security in its use for clasping the ends of bracelets, necklaces or the like.

The present improved clasp is particularly well adapted for use on expensive necklaces, neck-chains, link bracelets or the like since it provides a safer and more secure connection between the parts, being practically proof against accidental release whereby to insure against the loss of valuable jewelry.

As another feature of improvement the present clasp presents a smooth contour without sharp projections or parts liable to catch in the garments of the wearer or to injure the delicate flesh on which it is worn. The improved device also presents a highly ornamental and artistic appearance appropriate to high grade articles of jewelry on which it may be used.

While the present specification and drawings illustrate a preferred form of construction of the device, slight changes may be made in the shape and arrangement of its parts without departing from the spirit or scope of the invention. Therefore, without limiting myself in this respect, I claim:

An improved clasp for articles of jewelry or the like comprising a relatively flat elongated member having an eye at one end and a hook at the opposite end, and a tubular slide enclosing said member with its walls extended diametrically by the insertion of the member thereinto whereby to provide a frictional engagement therebetween, said slide slidable on the hook-member to close the mouth of the hook.

In testimony whereof I hereunto affix my signature.

GEORGE H. WATERHOUSE.
